UNITED STATES PATENT OFFICE.

ALVA J. FISHER, OF KANSAS CITY, MISSOURI.

LADLE FOR CASTING CAR-WHEELS.

SPECIFICATION forming part of Letters Patent No. 633,991, dated October 3, 1899.

Application filed August 9, 1898. Serial No. 688,281. (No model.)

To all whom it may concern:

Be it known that I, ALVA J. FISHER, of 5
Kansas City, Jackson county, Missouri, have
invented certain new and useful Improve-
ments in Ladles for Casting Car-Wheels, of
which the following is a specification.

My invention relates to that class of ladles
for casting car-wheels which discharge the
molten metal through an opening in the bot- 10
tom; and my object in this connection is to
generally improve upon the ladles at present
in use by providing a more reliable, strong,
and durable stopper-adjusting means and a 15
shield or guard to protect certain parts of the
device from the molten metal splattered in
the manipulation of the ladle, this shield or
guard thereby expediting the work.

Other objects of the invention will herein-
after appear and be pointed out in appended 20
claims, and in order that the invention may
be fully understood I will proceed to describe
it with reference to the accompanying draw-
ings, in which—

Figure 1 represents a detail vertical section
25 of the upper part of a ladle embodying my in-
vention. Fig. 2 is a top plan view of the same.
Fig. 3 is a side elevation showing the stopper-
operating mechanism. Fig. 4 is a horizontal
30 section taken just above the lever 6 in Fig. 3.
Fig. 5 is a detailed elevation of the trunnion-
bearing.

In said drawings, 1 designates the usual
cylindrical ladle, provided with a lining 2 and
a discharge-nozzle 3, arranged eccentrically
35 of its center (see Fig. 2) and provided with a
concave or segmental seat 4 in its upper end.

5 designates a slide-rest provided in its
outer face with a longitudinal dovetail groove
6 and bolted, as at 7, in a vertical position
40 to the ladle adjacent to the nozzle 3.

8 designates a slide dovetailed in the groove
6 and provided at its upper end with a hori-
zontal head 9, extending radially of the ladle,
and provided with a shield or hood for pre-
45 venting splattered metal from entering the
dovetail groove, and thereby rendering im-
possible the proper manipulation of the slide,
the improper manipulation of which is de-
structive to the car-wheel being cast. This
50 shield or hood consists of the side wings 10,
diverging downwardly from opposite sides of
the head 9 and bifurcated, as at 11, to accom-

modate the wall of the ladle. It also com-
prises the downwardly and inwardly sloping
wing 12, which projects down into the ladle, 55
and is preferably formed at its upper end and
outer side with a downwardly and outwardly
sloping wall 13, which tends to deflect inward
any molten metal which has splattered up be-
tween the wing 12 and the lining of the ladle. 60
By means of this shield or hood it will be seen
that it is practically impossible for molten
metal to enter the groove 6, and thereby inter-
fere with the proper manipulation of the slide.
If the metal should enter said groove and so 65
lidify at its lower end, it is obvious that it
would be impossible to check the flow of metal
from the ladle at the exact instant necessary,
and would thereby result in a ruined or defect-
ive car-wheel. Near its outer end the head 9 70
is provided with a vertical stud 14 and in ra-
dial alinement and inward of the same with a
second stud 15.

16 designates a plate provided with a hole
17, engaging stud 14, and a slot 18, engaging 75
stud 15, in order that said plate 16 may be lat-
erally adjusted as required. The upper ends
of these studs 14 and 15 are engaged by clamp-
ing-nuts 19 and 20, respectively, whereby
plate 16 is clamped in the required position. 80
The inner end of said plate is bifurcated, as
at 21, and bent to form bearing-cavities at op-
posite sides of the bifurcation and just in-
ward of the latter is provided with a vertical
stud 22, engaged at its upper end by a nut 23, 85
which secures plate 24 in position. This plate
24 is bifurcated at its inner end, as at 25, and
said end is bent to form downwardly-disposed
bearing-cavities. It is also bent downward
at its rear end to form the fulcrum or bearing- 90
point 26, which rests upon plate 16, thereby
giving clamping-nut 23 a leverage in order
that plate 24 may be clamped tightly upon the
oppositely-projecting trunnions 27 of the up-
right sleeve 28, the sleeve extending through 95
the registering bifurcations 21 and 25, with
its trunnions fitting in bearings formed in the
plates 16 and 24.

The stopper of the ladle consists of the head
29, of any suitable material and at its lower 100
side of hemispherical form in order that it
may effectually close the discharge-nozzle
when seated in recess 4, as indicated by dot-
ted lines in Fig. 3. This stopper is secured

in any suitable manner upon the lower end of rod 30, extending up through the sleeve 28 and engaged at its upper end by the clamping-nut 31, and surrounding said rod is a protective covering 32, which prevents the rod getting so hot that it will bend. This covering connects with the stopper 29 at its lower end and at its upper end is embraced by a cap 33, and between said cap and the lower end of the sleeve are washers 34. In practice the plate 16 is adjusted to dispose the sleeve 28 vertically over the center of the discharge-nozzle, so that when the stopper is clamped to the perpendicular sleeve it will close said nozzle, provided the slide occupies its depressed position, as shown in the drawings. As frequently happens, however, the rod 30 may not be perfectly straight, therefore throwing the head 29 of the stopper out of line with the upper end of rod 30 and the discharge-nozzle, with the result that an imperfect stoppage of the latter is effected. To correct this evil, the clamping-nut 23 is loosened and the trunnions 27 turned in their bearing to dispose the sleeve 28 at such an angle that the head 29 of the stopper will accurately fit in the recess 4 and effectually close the discharge-nozzle, or if the bend of the rod 30 is of such character that a lateral adjustment is necessary such adjustment can be effected by loosening nut 20 and swinging plate 16 to the right or left, as the case may be, on the pivot-pin 14, slot 18 engaging pin 15, permitting this adjustment to be made. If the bend in the rod should be neither directly inward nor lateral, but between the two, then it would be necessary to adjust the sleeve 28 in addition to the adjustment of plate 16. It will therefore be seen that this construction gives practically a universal adjustment of the stopper.

In order to manipulate the slide and the stopper connected thereto, I provide the following construction: 35 designates a pitman which is pivotally mounted at its upper end upon a stud 36, projecting from the slide, and at its lower end upon a pin or bolt 37, carried at the front end of a lever 38. Said lever is fulcrumed upon a stud or bolt 39, projecting from the slide-rest, and is provided with a handle 40, preferably detachable. By depressing said handle through the medium of the pitman 35 the slide and stopper are instantly raised and the molten metal permitted to flow out of the ladle through the discharge-nozzle thereof and into the mold. (Not shown.) When the handle is released, the slide gravitates back to its original position, and this gravitational action can be depended upon, owing to the fact that there is no possible chance for the molten metal obtaining access to the groove in which said slot operates.

The stopper-carrying rod 30 is preferably constructed of wrought-iron, and a protective covering for the same is made of a composition consisting of molding-sand, silica-sand, and fire-clay, preferably four parts each of

the molding and silica sand and one-fifth part fire-clay, dampened to render it plastic. This composition in practice is found to answer admirably. The ladle is constructed of steel, by preference, and the slide and rest therefor of cast-iron. It is to be understood, however, that I do not restrict myself to the use of any material or compositions of materials except as hereinafter indicated in the claims.

Having thus described the invention, what I claim as new, and desire to secure by Letters Patent, is—

1. A ladle for casting car-wheels, having an opening in its bottom, a vertically-grooved slide-rest secured to the ladle, a slide arranged in said groove and carrying a stopper for the opening of the ladle, and provided with a shield or hood for protecting the groove of the slide-rest from the entrance of splattered molten metal from the ladle, said shield consisting of downwardly-diverging bifurcated side wings, which overhang the upper end of the slide-rest and embrace the upper edge of the ladle, and a wing extending downward and inward of the ladle, substantially as described.

2. A ladle for casting car-wheels, having an opening in its bottom, a vertically-grooved slide-rest secured to the ladle, a slide arranged in said groove and carrying a stopper for the opening of the ladle, and provided with a shield or hood for protecting the groove of the slide-rest from the entrance of splattered molten metal from the ladle, said shield consisting of downwardly-diverging bifurcated side wings, which overhang the upper end of the slide-rest and embrace the upper edge of the ladle, and a wing extending downward and inward of the ladle, substantially as described.

3. A ladle for casting car-wheels, having an opening in its bottom, a slide, a stopper for the ladle-opening, a sleeve mounted upon the stem of said stopper and provided with outwardly-projecting trunnions, and a bifurcated bearing engaging said trunnions at opposite sides of the sleeve and carried by said slide, substantially as described.

4. A ladle for casting car-wheels, having an opening in its bottom, a stopper therefor provided with a stem, a slide, and means to operate the same, a plate secured to the slide and provided with a bifurcated bearing, a plate bolted upon the plate secured to the slide and provided with a companion bifurcated bearing and a fulcrum or bearing-shoulder, a sleeve upon the stopper-stem extending through said bifurcated bearing and provided with trunnions mounted in said bearings, and means to clamp the upper bearing-plate down upon the plate secured to the slide and upon said trunnions, substantially as described.

5. A ladle for casting car-wheels, having an opening in its bottom, a stopper therefor, a slide, and means to operate the same, studs

projecting upwardly from the slide, a plate carrying the stopper and resting upon the slide, pivoted upon one bolt and provided with a slot engaging the other, and clamp-nuts engaging said studs to secure said plate at the desired point of adjustment, substantially as described.

6. A ladle for casting car-wheels, having an opening in its bottom, a stopper therefor provided with a stem, a slide, and means to operate the same, a laterally-adjustable plate secured to the slide and provided with a bifurcated bearing, a plate bolted upon the plate secured to the slide and provided with a com-

panion bifurcated bearing and a fulcrum or bearing-shoulder, a sleeve upon the stopper-stem extending through said bifurcated bearing and provided with trunnions mounted in said bearings, and means to clamp the upper bearing-plate down upon the plate secured to the slide and upon the said trunnions, substantially as described.

In testimony whereof I affix my signature in the presence of two witnesses.
